Des. 192,538
Patented Apr. 3, 1962

192,538

THERMALLY INSULATED BOX

Gerson Meyer, Baltimore, Md., assignor to Life-Like Products, Inc., Baltimore, Md., a corporation of Maryland

Filed Dec. 15, 1960, Ser. No. 63,232

Term of patent 14 years

(Cl. D58—17)

FIG. 2.

FIG. 1.

FIG. 4.

FIG. 5.

FIG. 1 is a top plan view of a thermally insulated box, showing my new design;

FIG. 2 is a bottom plan view thereof;

FIG. 3 is a front elevational view thereof;

FIG. 4 is a rear elevational view thereof; and

FIG. 5 is an end elevational view thereof.

The end not shown is the same as the end shown.

I claim:

The ornamental design for a thermally insulated box, as shown and described.
